UNITED STATES PATENT OFFICE

2,441,664

MEANS FOR LENGTHENING SKIRTS

Lucille E. Hoagland, Rosemead, Calif.

Application August 9, 1947, Serial No. 767,791

1 Claim. (Cl. 2-211)

1

This invention relates to means for lengthening a skirt in order to adapt it to a change in style; and the invention is particularly applicable where the change in style does not require a great increase in the length of a skirt; and where the hem at the lower edge of the skirt has sufficient depth to enable it to be let down to give the required increase in the length of the skirt.

It is possible to lengthen a skirt by an amount equal substantially to the depth of its hem, letting down the hem and re-tailoring the lower end of the skirt by using a short hem and properly facing the hem on the inner side of the skirt. These operations, however, consume considerable time. One of the objects of this invention is to provide means which can be employed to facilitate the operations necessary to effect the lengthening of a skirt as suggested.

In practicing the invention, I provide a facing band, which finishes the lower edge of the skirt on its inner side; and one of the objects of the invention is to provide a facing band having a structure that will enable it to adapt itself to the width of the skirt at its bottom edge, thereby avoiding any possibility of the newly applied facing drawing the material of the skirt, or tending to pockers, or folds, in it.

Further objects of the invention will appear hereinafter.

The invention consists in the novel parts and combinations of parts to be described herein-after, all of which contribute to produce an efficient means for lengthening skirts.

A preferred embodiment of the invention is described in the following specification, while the broad scope of the invention is pointed out in the appended claim.

In the drawing:

Fig. 1 is a fragmentary vertical section taken through the lower edge of the skirt, and having a relatively deep hem; and which is adapted to be let down to lengthen the skirt.

Fig. 2 is a plan view of a short section of the means that I employ for facilitating the operation of lengthening a skirt.

Fig. 3 is a vertical section taken about on the line 3-3 of Fig. 2, and further illustrating the details of this article.

Fig. 4 is a sectional view similar to Fig. 1, but illustrating the relation of the parts after the lengthening operation has been effected through the agency of the means illustrated in Fig. 2.

Fig. 5 is an elevation of the parts illustrated in Fig. 4 as viewed from the inner side. This

2

view of course shows only a short section of the skirt after this operation is completed.

Referring more particularly to the parts, and especially to Fig. 1, 1 indicates the lower portion 5 of the skirt in vertical section. The lower end of the skirt is provided with a deep hem 2, the upper edge 3 of which is usually secured in place by binding 4, the lower portion 5 of which is stitched to the upper edge 3, and the upper edge portion of which is attached by blind stitches 6 to the material of the skirt.

In order to facilitate lengthening the skirt by an amount substantially equal to the depth of the hem 2, I provide a composite facing strip 15 7 illustrated in Figs. 2 and 3. This strip has a body 8 of suitable facing material, and this body is composed of bias material, that is to say, the direction of the weave of threads forming this facing, extends at an angle to the length of the goods. This angle of course is usually 45°. The upper edge of the facing body 8 carries a binding or tape 9 of relatively narrow width as compared with the width of the facing body 8. This binding 9 overlaps the upper edge 10 of the facing body 8, and the overlapped material is connected by stitches 11. The binding 9 as shown in Figure 2 has its threads extending "on the straight," that is with either the warp or weft extending longitudinally, in order that this binding be less extensible and thus afford a fixed anchor for the bias strip. In this way the binding 9 presents a projecting portion that extends beyond the upper edge 10 of the facing body 8, so as to present a free surface or area 12 beyond the edge 10. This projecting portion or area 12 is for the purpose of facilitating the attachment of this facing 7 on the inner side of the skirt when completing the lengthening operation.

In proceeding to lengthen a skirt such as illustrated in Fig. 1, the threads 6 are ripped out to free the upper edge of the binding 4 from the skirt, and any stitching such as the stitching 13 that secures the binding 4 to the edge 3 of the hem 2, is also ripped out. In other words, the hem 2 is completely freed so that it can extend down below the line 14 which represents the lower edge of the skirt as originally tailored. After accomplishing this, the lower edge 15 of the facing body 8 on the side 16 thereof, is laid over the lower edge of the hem 2 on its outer side, and either pinned or basted in place, after which these two edges are united together to form a seam, by longitudinal stitching 17. This stitching is applied near the edges so as to leave a hem 55 18 beyond the stitching on the material that

originally formed the hem 2, and also so as to leave a corresponding hem 18 on the facing body 8 of the facing strip 7. These hems are then pressed out flat, after which the facing strip 7 is folded back against the inner side of the skirt as illustrated in Fig. 4. In doing this, the facing strip 7 is lifted slightly so as to leave an edge 20 of material about a quarter of an inch wide between the bottom line 21 of the skirt and the location of the stitching 17. The upper edge of the binding 9 is then secured to the inner side of the material of the skirt, by blind stitching 22 (see Figs. 4 and 5).

It is evident that the composite facing strip 7 can be readily produced in large quantities by a continuous machine sewing operation in a factory. It should also be apparent that by using this composite strip to facilitate lengthening a skirt having a deep hem, it is only necessary to perform four simple operations, namely, ripping out the original binding 5 to let down the hem of the skirt; attaching the lower edge of the facing body 8 to the lower edge of the lengthened hem 2; pressing the hem thereafter; and then applying the blind stitches 22 to secure the upper edge of the binding 9 to the inner side of the skirt. And the bias material of the facing body 8 insures that the facing can stretch to adapt itself to the new bottom edge of the skirt, without drawing, and without puckering either the facing, or the lower edge of the lengthened skirt.

Many other embodiments of the invention may be resorted to without departing from the spirit of the invention.

I claim as my invention:

- 5 As a new article of manufacture, a separate piece of composite dress material for facilitating the lengthening of a skirt having a hem at its lower edge, including the combination of a facing band of bias material having a bottom edge adapted to be attached and hemmed to the lower edge of the lengthened skirt, and a relatively narrow binding attached longitudinally along the upper edge of said band overlapping said upper edge, said binding having its threads "on the straight," and extending above the same to present an area for the application of stitches for attaching the same to the material of the skirt.

20 LUCILLE E. HOAGLAND.
